UNITED STATES PATENT OFFICE.

JOHN RUTSON VAN TASSEL, OF GENEVA, NEW YORK, ASSIGNOR OF ONE-HALF TO STANDARD OPTICAL COMPANY, OF GENEVA, NEW YORK, A CORPORATION, AND ONE-HALF TO GUSTAV A. BADER, OF ROCHESTER, NEW YORK.

EYEGLASS-MOUNTING.

1,192,713.

Specification of Letters Patent. Patented July 25, 1916.

Application filed August 18, 1915. Serial No. 46,112.

To all whom it may concern:

Be it known that I, JOHN RUTSON VAN TASSEL, a citizen of the United States, and resident of Geneva, in the county of Ontario and State of New York, have invented certain new and useful Improvements in Eye-glass-Mountings, of which the following is a specification.

This invention relates to eyeglass-mountings of the rimless type.

One object of the invention is to provide an eyeglass-mounting of the kind in question with improved means for securing the mounting to the lenses. In rimless mountings as ordinarily constructed the lens is clasped tightly, at the end, between two ears of a U-shaped clip, these ears being perforated and connected by a screw which passes through a hole in the lens. To prevent the lens from rocking about the screw as a pivot the clip is usually provided with two arms, which extend upwardly and downwardly from its middle portion, in engagement with the edge of the lens.

In practice the arrangement just described has not been found wholly satisfactory, for the reason that, owing to the variation in the shape of the lenses which are used, and in the distance of the screw-hole in the lens from the edge of the lens, the arms above referred to do not always engage the edge of the lens closely. They may be caused to do so at their ends by bending them outwardly, but in that case more or less space may be left between the edge of the lens and the middle part of the clip, which results in an unsightly appearance. The arms may also, in this case, become bent inwardly again by use, thus permitting the lens to loosen.

In accordance with the present invention the lens-clip is provided with ears embracing the sides of the lens, but, for the purpose of steadyng the lens in the clip, arms are provided which extend upwardly and downwardly from one or both ears of the clip, and lie flat against the margins of the lens. These arms, on opposite sides of the lens, are independent of each other, and at their ends they have lugs bent inwardly so as to engage the edge of the lens.

Another object of the invention is to produce an eyeglass-mounting which may be conveniently made from a single piece or

blank of sheet-metal. The above-described construction of the lens-clip lends itself readily to such a one-piece construction, as it is possible to form the spring-bow by an upward extension of the metal from the middle part of each lens-clip, while the nose-guards may be formed by downward extensions of the metal from the same part.

Other objects of the invention, and the features of construction by which they are attained, will be set forth in connection with the following description of the illustrated embodiments of the invention.

In the accompanying drawings:—Figure 1 is a perspective view, from the rear, of an eyeglass-mounting embodying the present invention, with lenses fixed therein; Fig. 2 is a median transverse section, on a larger scale than Fig. 1, showing one of the lens-clips in inside end-elevation; Fig. 3 is a plan-view of the blank from which the one-piece mounting may be made in accordance with the present invention; Fig. 4 is a partial rear elevation of a mounting showing the invention in a modified form; and Fig. 5 is a section on the line 5—5 in Fig. 4, looking from right to left in the latter figure.

In the construction shown in Figs. 1, 2 and 3 each lens 10 is held between ears 11 forming part of one of the lens-clips, and these ears may be connected by a screw 12 in the usual manner. The clip, as a whole, is U-shaped in plan, being formed of sheet-metal and the ears being connected integrally by a middle portion 13, which is preferably remote from the edge of the lens so that by bending it the ears may be brought nearer together or farther apart, in accordance with the thickness of the lens which is to be held.

The characteristic feature of the invention resides in arms 14 which extend upwardly and downwardly from the edges of the ears 11, these arms being formed of the same piece of sheet-metal and being so located that they lie flat against the margins of the lenses. At their ends the arms are provided with lugs 15, bent inwardly or toward each other so as to engage the edge of the lens and thus steady it against any tendency to rock about the screw 12. The arms 14, owing to their form and position, have several advantages. In the first place, they are comparatively rigid, owing to the fact

that in them the width of the sheet-metal lies in the direction in which they are subjected to bending strains. In the second place, the arms always lie close against the lens, even though they be more or less bent to adapt them to the outline of the lens, and thus no unsightly space is left, between the clip and the edge of the lens, in which dirt may accumulate. In the third place, the fact 10 that the arms 14 are independent makes it possible for them to be used with lenses of different thickness, and also makes it possible, in the case of lenses of different thickness, to bend the arms 14 readily so that 15 they will lie flat against the margin of the lens, and makes it also possible in every case to bend the lugs 15 so that they will engage the edge of the lens closely.

A further advantage of the peculiar form 20 of clip above described resides in the fact that the lens-steadying arms do not spring from the middle part of the clip, and consequently extensions from this middle part may be formed for other purposes, thereby 25 facilitating the construction of a one-piece mounting. Such a construction is shown in Figs. 1, 2 and 3, wherein the spring-bow 16 extends integrally from the upper edges of the middle parts 13 of the lens-clips, while 30 the nose-guards 17 are carried by curved supports 18 which extend integrally from the lower edges of the middle parts 13.

Still another advantage of the form and 35 position of the arms 14 resides in the fact that they permit the lens-clips to be so shaped that the middle parts 13 are at a substantial distance from the edges of the lenses, so that the ears may be bent toward and from each other throughout a considerable space to adjust them to lenses of different thicknesses.

While my improved construction of the lens-clip is well adapted, as above described, for use in a one-piece mounting with a

spring-bow, it is also well adapted for use 45 with a built-up mounting having a rigid bridge. As shown in Figs. 4 and 5, the lens-clip may be formed with a middle portion 19 which lies close against the edge of the lens, and this middle portion may be 50 soldered or otherwise fixed to the end of a rigid bridge 20. Upon this bridge a nose-clamp lever 21 is pivoted in a well known manner.

I claim:—

1. In an eyeglass-mounting, a pair of ears 55 between which the lens is clipped, and independent arms extending upwardly and downwardly from the ears and lying flat against the margins of the lens, the arms 60 having lugs, at their ends, which are bent inwardly to engage the edge of the lens.

2. In an eyeglass-mounting, a sheet-metal member shaped and bent to form, integrally, 65 an ear which lies against the side of the lens, and independent arms extending upwardly and downwardly from the ear and lying flat against the margin of the lens, the arms 70 having lugs, at their ends, which engage the edge of the lens.

3. In an eyeglass-mounting, a sheet-metal member shaped and bent to form, integrally, 75 a U-shaped clip which embraces the lens, and independent arms which extend upwardly and downwardly from the ears of the clip and lie flat against the margins of the lens, the arms having lugs, at their ends, 80 which engage the edge of the lens.

4. In an eyeglass-mounting, a sheet-metal member shaped and bent to form, integrally, 85 a U-shaped clip which embraces the lens, independent arms extending upwardly and downwardly from each ear of the clip, a nose-guard extending from the bottom of the middle part of the clip, and a spring- 90 bow extending from the top of the middle part of the clip.

JOHN RUTSON VAN TASSEL.
